UNITED STATES PATENT OFFICE

ADOLFO CARUSO, OF NEW YORK, N. Y.

PORTABLE HARMONIUM

Application filed January 11, 1929. Serial No. 331,830.

This invention relates to musical instruments and more particularly refers to improvements in harmoniums and like instruments.

5 The primary object of this invention is to provide a portable harmonium of a novel and improved construction, which is very compact in design and ready at all times for instant operation.

10 Another object of the invention is to provide a novel and improved type of musical instrument of the reed type, which is particularly suitable for use by singers and vocal teachers as well as by persons engaged

15 in the tuning of musical instruments.

A further object of the invention is to provide, in a portable harmonium, certain novel and improved features, making it possible to set up and play the instruments 20 anywhere, for the purpose of rapidly going over a vocal selection, or for the purpose of instantly determining the right tone of a given note.

Other objects and advantages of the present 25 invention will more fully appear as the description proceeds and will be set forth and claimed in the appended claims.

Opera singers and other vocal artists, in order to keep in form, must practice at frequent 30 intervals, and usually require for this the assistance of a musical instrument, such as a piano, in determining the right tone for any given note. Voice practice is particularly necessary just before a performance, and even during the performance a piano or other suitable instrument is frequently concealed behind the scenes in order 35 to give the cue to singers when starting some particular aria or song.

40 On the other hand, the very nature of a singer's life calls for frequent traveling with stops at various places, so that this makes it difficult at times for the singer to 45 procure the needed facilities for voice testing.

My present invention affords the means of producing a given range of notes, whenever the user so desires; my apparatus being so 50 small and light and compact that it can be

placed on any table or chair or even on one's lap in order to operate it.

My invention is illustrated in the accompanying drawings, in which:

Fig. 1 is a view in perspective of a portable harmonium which is adapted to be operated by hand or by foot, with its cover open and partly broken away; 55

Fig. 2 is a cross sectional view of the same; 60

Fig. 3 is a view in perspective of the same in position for foot operation;

Fig. 4 is a detail view in perspective of the locking mechanism for the bellows;

Fig. 5 is a detail view in perspective of the 65 swell board from the rear;

Fig. 6 is a plan view of another device embodying my invention, adapted for electric operation by means of a plug and socket connection; 70

Fig. 7 is a cross sectional view of the same through line 7—7 of Fig. 6.

The chief characteristics of my device are its extreme compactness and its instant readiness for operation. The same essentially 75 comprises a portable case with all the operating parts mounted therein, said parts being permanently set in their operative relation to one another and making it thus possible to play the instrument as soon as its cover is 80 open.

Referring to the device shown in Figs. 1 to 5, 10 designates a frame structure which is preferably in the form of an ordinary suit case, comprising a case proper 11 and a cover 12 hinged thereto at 13, said case being provided with a handle 14. 85

The lower part of the case is enclosed to form an air chamber 15, by a horizontal partition 16 and a board 17, and the upper part 90 of the case is divided into a front chamber 18 and a rear chamber 19 by vertical boards 20, 21.

Chamber 19 extends for the entire length of the case and accommodates a keyboard 22 and the sound controlling devices operated by its keys 23, which may be of any conventional type. For instance, the board 17 may be provided with a set of elongated openings 24, one underneath each key of the keyboard, 100

said openings being normally covered by valves 25.

Above each opening 24 is provided a reed such as 26, said reeds being enclosed in a chamber 27, communicating at the rear with chamber 19.

The rear outlet 28 of chamber 19 is controlled by a movable swell board, which is hinged at 30 as shown at Fig. 5.

Said swell board is normally set in its closed position shown, but may be forced open to a position where a spring catch 31 will enter and interlock with an opening 32, so as to maintain the swell board in its open position 29' shown in dotted lines in Fig. 2.

The keys 23 are divided at the rear as shown at 30 and are provided with guide pins 31. Actuating rods 32 are interposed between each key and the underlying valve 25, said rods projecting through and being guided by a guide board 33. Valves 25 are normally held in their closed position by springs 34 as shown.

By providing a supply of air under pressure within chamber 15, it will be possible to produce the entire range of notes for which the keyboard is intended. In the structure shown, air is forced into chamber 15 by means of a pumping bellows 35, which is set within chamber 18 and which can be operated by up and down movement of the hand.

The top board 36 of the bellows is normally retained in its contracted position by means of a latch or hook 37 engaging a hook 38 associated with said board 36, as shown in Fig. 4. Latch or hook 37 is pivotally mounted at 39 and can be moved to one side to free the bellows whenever desired.

In order to operate the device, therefore, it is sufficient to lay the suit case structure on a table and to open cover 12; by releasing hook or latch 37, the device is then made ready for instant operation. The singer may test his or her voice by operating the bellows 35 with one hand the depressing the key corresponding to the desired note with the other, so that practicing may be done without any outside assistance; it is also possible if desired, for the singer to sit down and to place the case on his or her lap while practicing, as will be understood.

The device may preferably also comprise means for supporting sheets of music; for instance, a ledge 40 may be hinged to the inside of the cover as shown at 41, said ledge normally resting flat against the inner surface of the cover as shown in dotted lines at 40', and being tiltable so as to extend frontwardly therefrom, as shown in full lines in Figs. 1 and 2.

The device may also be made operable either by hand or by foot, by providing the upper board 36 of the bellows with a sliding board 42 movable in a front to rear direction.

Said sliding board carries the hook 38' and when said board is in its extended position shown in Fig. 3, a pedal 43 can be connected thereto by means of a preferably adjustable connection 44. This arrangement enables the operator to use both hands and therefore permits of completing a full score within the limits consented by the range of the keyboard.

Instead of or besides the bellows illustrated and described, the device may be provided with electrically operable means for supplying air to the air chamber, said means being adapted for ready connection to or disconnection from any convenient outlet by means of a plug and socket connection of the ordinary type. An arrangement of this kind is illustrated in Figs. 6, 7, in which 50 designates the case provided with a cover 51 hinged thereto at 52. Like in the previous case, the bottom part of the case is enclosed by a horizontal partition 53 and a board 54 to form an air chamber 55.

The keyboard is in this case arranged at the front of the case, and comprises keys 56 controlling valves 57 as previously explained, said key board being also equipped with a swell board 58.

Within the rear part of chamber 55, is enclosed an electric motor 59' directly connected to an air pump 60, which is provided with an inlet 61 communicating with the outside atmosphere and an outlet 62 opening within chamber 55. A device of this type can be connected to any suitable electric outlet by means of a plug and socket connection and flexible cable 63, 64.

The socket leading to the electric motor is preferably mounted within the case, for instance, near one end of board 53 as shown, so that the device cannot be connected if the cover is locked.

Since electric outlets are now available in practically every hotel or home, it is possible to set the device for use over extended periods, by maintaining a continuous supply of air. The air chamber may if desired, be provided with an excess pressure valve, not shown.

From the foregoing it will be seen that I provide a portable harmonium which is entirely self contained and which affords a means of producing sustained notes lasting a sufficiently long period of time to serve the purpose for which the instrument is intended. Minor changes in the design and construction of my device may be introduced without departing from the inventive idea. The drawings will therefore be understood as being intended for illustrative purposes only and not in a limiting sense. Therefore, I reserve the right to carry my invention into practice in all those ways and manners which may enter, fairly, into the scope of the appended claims.

I claim:

1. In a device of the class specified, a box-like structure of the suit case type, comprising an open top body and a cover therefor, an enclosed air chamber within said body, and hand operable means normally concealed by said cover also mounted within said body, adapted to supply air under pressure to said chamber, said means becoming exposed and operable upon the opening of said cover. 70
- 10 2. In a device of the class specified, a box-like structure of the suit case type, comprising an open top body and a cover therefor, an enclosed air chamber within said body, and a hand operable bellows normally concealed by said cover also mounted within said body, adapted to supply air under pressure to said chamber, said bellows becoming exposed and operable upon the opening of said cover. 75
- 15 3. In a device of the class specified, a box-like structure of the suit case type, comprising an open top body and a cover therefor, an enclosed air chamber within said body, a hand operable bellows also mounted within said body, adapted to supply air under pressure to said chamber, a pedal, and means for connecting said pedal to said bellows. 80
- 20 4. In a device of the class specified, a box-like structure of the suit case type, comprising an open top body and a cover therefor, an enclosed air chamber within said body, a hand operable bellows also mounted within said body, adapted to supply air under pressure to said chamber, a member movably associated with said bellows, adapted to project outwardly of said body, and a detachable pedal connection for said member. 85
- 25 5. In a device of the class specified, a box-like structure of the suit case type, comprising an open top body and a cover therefor, an enclosed air chamber within said body, a hand operable bellows also mounted within said body, adapted to supply air under pressure to said chamber, a member slidably mounted on said bellows, adapted to be moved in and out of said body, and a detachable pedal connection for said member. 90
- 30 6. In a device of the class specified, a box-like structure of the suit case type, comprising an open top body and a cover therefor, an enclosed air chamber within said body, a hand operable bellows also mounted within said body, adapted to supply air under pressure to said chamber, and means for locking said bellows in its contracted position. 95
- 35 7. In a device of the class specified, a box-like structure of the suit case type, comprising an open top body and a cover therefor, an enclosed air chamber within said body, hand operable means normally concealed by said cover also mounted within said body, controlling the supply of air to said chamber, and a keyboard and sound producing devices controlled thereby, also mounted within said body, said air controlling means and key- 100
- 40 board becoming exposed and operable upon the opening of said cover. 105
- 45 8. In a device of the class specified, a box-like structure of the suit case type, comprising an open top body and a cover therefor, an enclosed air chamber within said body, hand operable means normally concealed by said cover also mounted within said body, controlling the supply of air to said chamber, a keyboard and sound producing devices controlled thereby, also mounted within said body, and a music supporting ledge carried by the inner surface of said cover, said air controlling means and keyboard becoming exposed and operable upon the opening of said cover. 110
- 50 9. In a device of the class specified, a box-like structure of the suit case type, comprising an open top body and a cover therefor, an enclosed air chamber within said body, and means optionally operable either by hand or foot also mounted on said body, adapted to supply air under pressure to said chamber. 115
- 55 10. In a device of the class specified, a box-like structure of the suit case type, comprising an open top body and a cover therefor, an enclosed air chamber within said body, and bellows optionally operable either by hand or foot also mounted within said body, adapted to supply air under pressure to said chamber. 120
- 60 11. In a device of the class specified, a box-like structure of the suit case type, comprising an open top body and a cover therefor, an enclosed air chamber within said body, bellows optionally operable either by hand or foot also mounted within said body, adapted to supply air under pressure to said chamber, and a keyboard and sound producing devices controlled thereby, also mounted within said body. 125

ADOLFO CARUSO.
